UNITED STATES PATENT OFFICE.

FRANK G. WHITE, OF CHICAGO, ILLINOIS, ASSIGNOR OF ONE-HALF TO HENRY D. LEWIS, OF CHICAGO, ILLINOIS.

MATCH-SAFE.

No. 908,923.

Specification of Letters Patent.

Patented Jan. 5, 1909.

Application filed February 8, 1907. Serial No. 356,455.

To all whom it may concern:

Be it known that I, FRANK G. WHITE, a citizen of the United States, and a resident of Chicago, in the county of Cook and State of Illinois, have invented certain new and useful Improvements in Match-Safes, of which the following is a clear, full, and exact description.

My invention relates to match safes and more particularly to that type in which a number of matches are placed in a holder or reservoir and dispensed therefrom not more than one at a time to the user.

In cigar stores, drug stores, and other public places it has become a nuisance as well as an item of expense to provide matches for smokers, for when a box is placed on the counter customers are generally not content to take one or two matches but help themselves to a handful. Such reckless appropriation of matches requires the constant refilling of match boxes, and involves quite an expense, which would be avoided if the smoker could take only one match at a time.

The object of my invention is to provide a match-safe by the use of which this annoyance will be avoided and the expense of supplying matches materially reduced.

Another object is to so construct the device that the end of a cigar may be automatically cut at the same time the match is being delivered from the reservoir. This I accomplish by the means hereinafter fully described and as more particularly pointed out in the claims.

In the drawings:—Figure 1 is a front elevation of my improved match safe. Fig. 2 is a transverse vertical section thereof taken on dotted line 2—2, Fig. 1. Fig. 3 is a view similar to Fig. 1 having the front-plate removed to disclose the operating mechanism for elevating and dispensing the matches.

Referring to the drawings, A represents a base-plate of any suitable design from about the center of which is mounted a standard B consisting of a vertical plate for supporting the improved match safe. The front face of this plate is either cut away or its vertical side edges are provided with marginal beads *a, a*, so that when closed by a removable front-plate C a narrow space will be left between the two in which the match expelling mechanism is housed, as will hereinafter be more fully described. Made integral with

the upper portion of the standard B and extending to the rear of the vertical plane thereof is a suitable match compartment D of any desired shape in cross section but provided with an inclined bottom *g* that is arranged at an angle inclined to the said standard B. The rear of this compartment is cut away as shown, and is normally closed by a segmental hood-shaped door E secured to the end-walls by suitable pivots so that it will close itself by gravity. The front of the compartment is closed by the upper portion of the front-plate C that extends up to the top of the box and is provided with a horizontally elongated slot for the exit of the matches.

The means for expelling the matches one at a time from the reservoir consist of a slide F mounted and reciprocating vertically in the space formed between the front-plate C and the standard above described. Said slide is adapted to be raised and lowered through the medium of a goose-neck or S-shaped operating lever G that has its inner end *g'* provided with an enlargement that is seated in and articulates with the edges of a suitable cut recess *f* in the face of said slide. Lever G is pivoted mediate its ends between two lugs *b', c'*, projecting from the side edge of the front-plate and standard respectively. The top edge of slide F rises just to the lowermost portion of the match compartment when in its normal position and is preferably beveled or grooved outwardly sufficiently to provide a seat for a single match. When lever G is depressed the slide is raised and the match seated in the groove is elevated until it reaches the elongated slot *e* at the top of the compartment when it will roll off the upper edge of the slide and gravitate through said opening into a suitable trough-shaped basket H that is provided at the top of the front-plate C just below said slot.

The pivot lug *b'* preferably extends a slight distance beyond and below the pivot of lever G and has a countersunk opening *h* therein and said lever is provided with a cutter-blade or sharpened edge *h'*, which as said lever is depressed passes close to said opening and will shear the end of a cigar inserted in opening *h* simultaneously with the delivery of a match from the compartment.

If desired the shape and construction of the match compartment may be changed.

The rear door may be omitted by closing the opening and filling the compartment through the slot in the front of the device. Such changes I desire as contemplated within the 5 scope of my invention.

What I claim as new is:—

1. A match-safe comprising a normally closed match compartment having its front wall cut away, a standard supporting said 10 compartment provided with marginal beads, a removable front-plate fitted on the front of said standard and partially closing the cut away portion of said compartment, a reciprocal slide operating between said plate and standard having a recess therein opening towards one side thereof, and a pivoted lever 15 operating in said recess for elevating and delivering matches from said compartment through the opening above said front-plate.
2. A match-safe comprising a normally closed match compartment having its front wall cut away and its bottom inclined toward one side, a standard supporting said compartment provided with marginal beads, a 20 removable front-plate fitted on the front of said standard and partially closing the cut away portion of said compartment, a reciprocal slide operating between said plate and standard having a recess therein opening towards one side thereof, and a pivoted lever 25 operating in said recess for elevating and delivering matches from said compartment through the opening above said front-plate.
3. A match-safe comprising a normally closed match compartment having its front wall cut away, a standard supporting said compartment provided with marginal beads, a removable front-plate fitted on the front of said standard and partially closing the cut 30 away portion of said compartment, a reciprocal slide provided with a recess opening towards one side thereof and operating between said plate and standard having its upper edge beveled and inclined outwards, and a pivoted lever operating in said recess for elevating said slide and delivering matches from said compartment through the opening 35 above said front-plate.
4. A match-safe comprising a normally closed match compartment having its front wall cut away and its bottom inclined toward one side, a standard supporting said compartment provided with marginal beads, a removable front-plate fitted on the front of 40 said standard and partially closing the cut away portion of said compartment, a reciprocal slide provided with a recess opening towards one side thereof and operating between said plate and standard having its upper edge beveled and inclined outwards, and a pivoted lever operating in said recess for elevating said slide and delivering matches from said compartment through the opening 45 above said front-plate.
5. A match-safe comprising a normally closed match compartment having its front wall cut away and its bottom inclined toward one side, a standard supporting said compartment provided with marginal beads, a removable front-plate fitted on the front of 50 said standard and partially closing the cut away portion of said compartment, a reciprocal slide provided with a recess opening towards one side thereof and operating between said plate and standard having its upper edge beveled and inclined outwards, and a pivoted lever operating in said recess for elevating said slide and delivering matches from said compartment through the opening 55 above said front-plate.
6. A match-safe comprising a normally closed match compartment having its front wall cut away and its bottom inclined toward one side, a standard supporting said compartment provided with marginal beads, a removable front-plate fitted on the front of 60 said standard and partially closing the cut away portion of said compartment, a reciprocal slide provided with a recess opening towards one side thereof and operating between said plate and standard having its upper edge beveled and inclined outwards, and a pivoted lever operating in said recess for elevating said slide and delivering matches from said compartment through the opening 65 above said front-plate.

5. A match-safe comprising a normally closed match compartment having its front wall cut-away and its bottom inclined toward one side, a standard supporting said compartment provided with marginal beads, a removable front-plate fitted on the front of 65 said standard and partially closing the cut away portion of said compartment, a reciprocal slide provided with a recess opening towards one side thereof and operating between said plate and standard having its upper edge beveled and inclined outwards to 70 form a seat for elevating and delivering matches from said compartment through the opening above said front-plate, and a pivoted operating lever articulating in the recess in 75 said slide for raising and lowering the same.

6. A match-safe comprising a normally closed match compartment having its front wall cut away and its bottom inclined toward one side, a gravity-closed door through 80 which access is obtained to said compartment, a standard supporting said compartment provided with marginal beads, a removable front-plate fitted on the front of 85 said standard and partially closing the cut away portion of said compartment, a reciprocal slide operating between said plate and standard having a recess therein opening towards one side thereof, and a pivoted lever 90 operating in said recess for elevating and delivering matches from said compartment through the opening above said front-plate.

7. A match-safe comprising a normally closed match compartment having its front wall cut away and its bottom inclined toward 95 one side, a gravity-closed door through which access is obtained to said compartment, a standard supporting said compartment provided with marginal beads, a removable front-plate fitted on the front of 100 said standard and partially closing the cut away portion of said compartment, a reciprocal slide provided with a recess opening towards one side thereof and operating between said plate and standard having its upper edge beveled and inclined outwards, and a pivoted lever operating in said recess for elevating said slide and delivering matches from said compartment through the opening 105 above said front-plate.

8. A match-safe comprising a normally closed match compartment having its front wall cut away and its bottom inclined toward one side, a gravity closed door through which access is obtained to said compartment, a standard supporting said compartment provided with marginal beads, a removable front-plate fitted on the front of 110 said standard and partially closing the cut away portion of said compartment, a reciprocal slide provided with a recess opening towards one side thereof and operating between said plate and standard having its upper edge beveled and inclined outwards, and a pivoted lever operating in said recess for elevating said slide and delivering matches from said compartment through the opening 115 above said front-plate.

per edge beveled and inclined outwards to form a seat for elevating and delivering matches from said compartment through the opening above said front-plate, and a pivoted 5 operating lever articulating in the recess in said slide for raising and lowering the same.

In testimony whereof I have hereunto set

my hand and seal this 31 day of January, 1907.

FRANK G. WHITE. [L. s.]
